UNITED STATES PATENT OFFICE.

PETER J. MCGUIRE, OF BLAIRSVILLE, PENNSYLVANIA, ASSIGNOR TO THE CHAMPION SANITARY ENAMEL WARE CO., A CORPORATION OF PENNSYLVANIA.

MOLDING-FLASK.

SPECIFICATION forming part of Letters Patent No. 721,728, dated March 3, 1903.

Application filed March 21, 1902. Serial No. 99,295. (No model.)

To all whom it may concern:

Be it known that I, PETER J. MCGUIRE, a citizen of the United States, residing at Blairstown, in the county of Indiana and State of Pennsylvania, have invented a new and useful Improvement in Molding-Flasks, of which improvement the following is a specification.

This invention relates to improvements in molding - flasks, particularly to flasks employed in molding metal bodies having outwardly-extended flanges, such as bath-tubs.

In the art of molding such bodies as bath-tubs it is difficult to suspend or retain the sand in the cope or cheek portion of the mold forming the flange, and the usual custom in such cases is to closely embed a plurality of spikes in the sand about said flange, which "spiking" is not always an effective remedy, as more or less of the spikes come in contact with the rammer, displacing the same or shattering the sand thereabout, which when relieved of the pattern require dressing. Again, if the sand be overly damp the spike method is frequently of no avail. Besides, the time required to thus spike the mold and loss of spikes materially reduce the profits of manufacture.

My object therefore is to provide a simple and practical means in connection with the flask whereby the above difficulties are overcome.

In the accompanying drawings I have by various views illustrated my improvements for retaining the sand in the flask where the flange of the body is to be formed, in which drawings—

Figure I is an inverted plan view. Fig. II is a transverse sectional view through the same, showing its application to the pattern or molding machine, the latter being also shown partly in section. Fig. III is a perspective view of a portion of said flask. Fig. IV is a perspective view of a portion of a flask, showing variations in the means employed for the retention of the sand. Fig. V is a transverse sectional view of a portion of a flask and pattern, showing the manner of spiking as heretofore practiced for the retention of the sand at the tub-flange.

Further referring to said drawings for a detailed description of said views, particularly

Figs. I, II, and III, the numeral 1 designates a flask or cheek, 2 a bath-tub pattern, having the usual flange 3 extending thereabout, and 4 the molding apparatus to which said pattern is fitted and forms a part thereof. Arranged at intervals all the way around the interior of said flask above the parting-surface thereof are a plurality of inwardly-extended pins or sand-anchors 5, having their free ends turned downwardly in the form of a hook, so as to extend into but not in contact with the hollow side of the flange extending about the tub-pattern. The opposite ends of said pins or anchors are threadably fitted within the flask-walls and secured by nuts 5', so that they may be adjusted to proper positions over said flange. These pins or sand-anchors I prefer shall be "roughed" upon their surfaces or be of such surface formation to cause a retention of the sand and such distance apart as will permit the free use of the rammer in ramming up the mold. At Fig. IV, I have shown two of a number of variations or equivalents in sand-anchors for performing the same functions, that designated at 7 being provided with a head, which anchor may be cast into or otherwise secured to the flask-walls, while that designated as 8 is shown as being integral with the flask and provided with a serrated surface.

At Fig. V, where the method heretofore practiced for the retention of the sand about that portion of the mold forming the tub-flange is shown, the numeral 9 designates one of a number of spikes, which is shown as embedded in the sand.

By providing the flask with or otherwise arranging therein a plurality of fixed rods or anchors, spaced such distance apart as to not interfere with the ramming up of the mold, it will be readily apparent that the labor and expense incurred in the manufacture of bath-tubs and bodies of like character are greatly reduced.

It is possible that other variations in the form of anchors and manner of retaining the same in operative position may be made to perform the same function, all of which would fall within the limits of my invention and considered as equivalents.

Having thus fully shown and described my

invention, what I claim as new, and desire to secure by Letters Patent, is—

1. A flask member adapted for service in molding the outer surface of hollow bodies having a rim of approximate concavo-convex form in cross-section extending outwardly about the edge thereof, comprising a sand-mold receptacle having projecting inwardly and direct from the ends and side walls a multiplicity of permanent sand-retainers the inner or free extremities of which are adapted to extend into and be buried in the sand ridge of the mold edge forming the concave side of the body-rim only.
- 15 2. A flask member adapted for service in molding the outer surface of hollow bodies having a rim of approximate concavo-convex form in cross-section extending outwardly about the edge thereof, comprising a sand-mold receptacle having projecting inwardly and direct from the ends and side walls a multiplicity of permanent hook-shaped sand-retainers the inner or turned-over ends of

which are adapted to extend into and be buried in the sand ridge of the mold edge 25 forming the concave side of the body-rim only.

3. A molding-flask having around the ends and side walls thereof adjacent to one edge a multiplicity of horizontally-disposed inwardly-projecting sand-retainers each independently fixed to said walls and capable of being horizontally adjusted.

4. A molding-flask having around the ends and side walls thereof adjacent to one edge 35 a multiplicity of horizontally-disposed hook-shaped inwardly-projecting sand-retainers each independently fixed to said walls and capable of being horizontally adjusted.

In testimony whereof I have hereunto 40 signed my name in the presence of two subscribing witnesses.

PETER J. MCGUIRE.
